AGING APPARATUS FOR TRANSISTORS

Wentworth D. Boynton, Wyomissing, and Paul L. Mueller, Temple, Pa., assignors to Western Electric Company, Incorporated, New York, N. Y., a corporation of New York

Application May 27, 1954, Serial No. 432,775

4 Claims. (Cl. 29—25.3)

This invention relates to aging apparatus for transistors.

In the manufacture of transistors, as is common practice with vacuum tubes and other electrical components, it is necessary that they be electrically aged by applying specific voltages, depending on the code of the transistor, to the electrodes thereof for a pre-determined period of time.

It is, therefore, the principal object of the invention to provide an aging cabinet in which transistors of a variety of codes or types may be conveniently aged.

In accordance with the above object, the cabinet is provided with means for adjusting the voltages applied to the transistors, receptacles for receiving any of a series of transistor aging trays each wired for and loaded with transistors of a particular type or code and designed for spaced-stacking, a fan for circulating air around the trays and a timer to cut off the power after a selected aging period.

According to an important feature of the invention the inadvertent application of excessive potential to the transistors is prevented by an electrical interlock which requires the operator to return the voltage adjusting means to low voltage position before the aging circuits can be energized.

Another important feature of the apparatus is that power is automatically cut off and an indicator is operated if the cabinet doors are opened thereby assuring that no trays have been added or removed during the aging cycle.

According to another feature of the invention, in order to facilitate repairing the trays, in case of any trouble developing therein, the transistor sockets are mounted in sub-assemblies each with its proper resistors. The sub-assemblies may be removed as a unit and may be conveniently repaired or replaced.

These and other features of the invention will be more fully understood from the following description taken in conjunction with the accompanying drawing, in which:

Fig. 1 is a front view of the cabinet with one of the doors open showing several trays stacked therein;

Fig. 2 is a side view of the cabinet of Fig. 1 showing a fan and adjustable shutters for controlling the circulation of the air over each tray in the cabinet;

Fig. 3 is a plan view of one of the trays;

Fig. 4 is a plan view of one of the sub-assemblies for a tray;

Fig. 5 is a view of the tray of Fig. 3 along the plane of line 5—5;

Fig. 6 is a schematic diagram of a sub-assembly, and

Fig. 7 is a schematic diagram of the electrical circuit by which the apparatus is controlled.

As illustrated in the drawing, the cabinet in general comprises a steel frame structure having a control panel 8 on which the meters, rheostats or variable autotransformers, indicators and circuit breaker are mounted, a sheet metal divided, tray receiving portion 9 having open meshed doors 43, a housing for a ventilating fan 10 and a power supply housing portion 11.

2

As seen in Fig. 2 baffle elements 75 are disposed at the back of each tray compartment 12 and are individually mounted to the cabinet to control the amount of air passing through each compartment, the angular setting of each baffle being determined experimentally to give equal circulation of air around each tray. The air is taken in through the open mesh doors 43, passes through the tray compartments 12 into a chamber 76 in the back of the cabinet and is exhausted through the aperture in the rear of the cabinet for the fan.

Trays 14 contain a plurality of sub-assemblies 15 mounted by bolts 18 to a top plate 17 having a plurality of apertures for the transistor sockets 70. Each of the sub-assemblies 15 is provided with 6 sockets 70 having 3 contact elements 19, 20 and 21 for receiving transistors having emitter, collector, and base electrodes respectively. The emitter and collector contacting elements 19 and 20 are connected through appropriate biasing resistors 22 and 23 to conductors 24 and 25 respectively which in turn are attached to tray bus bars 26 and 27 mounted by insulating bracket 28 along one side of the top plate 17. The bias resistors 22 and 23 are chosen for the particular adjusted voltage of the tray bus bars and the code of transistors to be aged. Thus the trays may be wired for transistors of different codes, an identification plate 42 being provided on the front of the tray for noting the code for which the tray is wired.

Lamps 29 and 30 on the front panel 31 of the tray are connected between ground potential and the bus bars 26 and 27 through wires 32, 33 and 34 for indicating the application of power to bus bars 26 and 27. The tray bus bars 26 and 27 are connected to the cabinet power source and the tray frame is connected to ground potential through plug 35 mounted at the back end of the tray which engages any one of a plurality of corresponding sockets in the cabinet. The electrical circuit for energizing these sockets will be discussed below.

By providing stand-offs 37 mounted on each corner of the top plate 17 of each tray and corresponding receiving wells 40 in each corner of the bottom plates 37, it is possible to stack loaded trays awaiting electrical aging in any convenient place outside of the cabinet without requiring a compartmented holder.

The control circuit shown in Fig. 7 is used for supplying the appropriate tray bus bar voltages to sockets 36 from a 110 volt, 60 cycle per second source 48. This circuit includes a timer 59 for opening the power supply circuit at the end of a pre-set aging period and also includes means for preventing the application of excessive initial voltages, indicates power failure and removal or addition of trays during the aging period which would require the opening of the cabinet doors.

Specifically, the sockets 36 are energized from emitter and collector supply rectifiers 44 and 45 which in turn are energized by rheostats or variable autotransformers 46 and 47 respectively. The inputs to the autotransformers are connected in parallel and the application of power thereto is controlled by relay 51 which must be operated to connect the source 48 thereto through power distribution lines 63 and 64. A time meter 52 and an indicator 53 are bridged across the inputs to the autotransformers. The time meter 52 records the aging time while the indicator 53 conveniently shows that the aging circuit is energized. Before control relay 51 can be energized to close the aging circuit, autotransformer switches 54 and 55, door switches 56 and 57 and switch 58 controlled by timer 59 must be closed. Switches 54 and 55 are on autotransformers 46 and 47 respectively and are closed only when the autotransformers are set for minimum or a reduced output voltage. This is one type of simple electrical interlock which requires the

operator to return the autotransformers to minimum output settings to prevent the inadvertent application of high initial voltages to the transistors in the trays. Once the relay 51 is operated the autotransformers may be adjusted as required since, by operation of the relay 51, switches 54 and 55 are by-passed from the relay energizing circuit by lead 60, operated contact 61 of relay 51 which is jumpered to contact 62 connected to the distribution line 63.

Door switches 56 and 57 are closed when the doors are closed and opening either door for the removal or addition of trays during the aging cycle will open the control relay circuit and thereby open the aging circuit. Before the aging circuit can be closed again the autotransformers must be returned to minimum output settings and the doors must be closed. The timer 59, of course, must be adjusted to the prescribed setting in order to close its contact 58. The fan motor 65 is connected in parallel with the relay 51 winding so that air will be circulated through the cabinet whenever the relay is energized.

Distribution lines 63 and 64 of the aging control circuit are connected to the source 48 through a circuit breaker 66, mounted for convenience on the control panel 8. An indicator lamp 68 bridged across lines 63 and 64 is energized when the lines 63 and 64 are connected to the source. Once the aging cycle has been started if the cycle is interrupted by power failure or by one of the cabinet doors being opened, an indicator 69, which is connected to line 64 through timer switch 58 and to line 63 through the released contact 61 of the relay 51, is energized.

As seen in Figs. 1 and 7 voltmeter 71 and 72, connected across the output of the emitter and collector supply rectifiers 44 and 45, are provided for indicating the adjusted outputs of the emitter and collector supplies respectively. In addition, a multi-range ammeter 73 is provided in the output of the collector supply rectifier.

It is to be understood that the above described arrangements are simply illustrative of the application of the principles of the invention. Numerous other arrangements may be readily devised by those skilled in the art which will embody the principles of the invention and fall within the spirit and scope thereof.

What is claimed is:

1. Transistor aging apparatus comprising a cabinet, means for circulating air through the cabinet, adjustable sources of transistor electrode voltages for the cabinet, a plurality of trays for the cabinet, said trays having transistor receiving sockets and circuits therefor including electrode bias impedances, means for connecting said circuits to the sources in the cabinet, means for spaced-stacking

the trays in the cabinet to permit engagement of the connecting means, means including an adjustable timer for de-energizing the sources after a selected aging period, switching means controlled by the power sources to permit energizing the sources only when the sources are set for reduced output and means for by-passing the switching means when the sources are energized.

2. Apparatus according to claim 1 in which the sockets are mounted on the trays in removable sub-assemblies, each socket having its respective bias impedances wired thereto and the connecting means include bus bars in the trays to which the sub-assembly wiring is connected.

3. Transistor aging apparatus comprising a plurality of trays having transistor receiving sockets and wiring for a particular code of transistors, a cabinet having a tray receiving portion, means for circulating air through the cabinet, sources of transistor electrode voltages for the cabinet, a rheostat in each of the sources for varying its output voltage, means for connecting the tray wiring to the sources in the cabinet, means for spaced-stacking the trays in the cabinet to permit engagement of the connecting means, means including an adjustable timer for de-energizing the sources after a selected aging period, switching means controlled by the rheostats to permit energizing the sources only when the rheostats are set for lower than normal outputs for the sources, and means for by-passing the switching means when the sources are energized.

4. Transistor aging apparatus comprising a cabinet, means for circulating air through the cabinet, sources of transistor electrode voltages for the cabinet, a variable autotransformer in each of the sources for varying its output voltage, an energizing source of power for the electrode sources, a relay for connecting the energizing source to the electrode sources, an energizing circuit for the relay including switches controlled by the autotransformers to permit operation of the relay to connect the energizing source to the electrode sources only when the autotransformers are set for lower than normal output for the sources, means for by-passing the switches when the electrode sources are energized, a plurality of trays having transistor receiving sockets and wiring for a particular code of transistors, means for connecting the tray wiring to the sources in the cabinet, means for spaced-stacking the trays in the cabinet to permit engagement of the connecting means, means including an adjustable timer and contacts controlled thereby connected in the relay energizing circuit for opening said circuit after a selected aging period.
